UNITED STATES PATENT OFFICE

OTTO HEINRICH DRÄGER, OF LUBECK, GERMANY

OXYGEN BREATHING IMPLEMENT, PARTICULARLY FOR AERONAUTS

Application filed February 5, 1929, Serial No. 337,691, and in Germany February 21, 1928.

Breathing devices used by aviators are well known. It is requisite that they be constructed so as to permit the admission into the device of air from the atmosphere to be breathed by the aviator in addition to the oxygen supplied by the device itself.

It has been found extremely difficult to admit air from the outside in proper quantities so as to provide the aviator with the requisite amount to be breathed with the oxygen supplied by the device itself.

Heretofore this has been accomplished, but imperfectly, by masks which fit but loosely against the face or by masks having apertures against the face or by masks having apertures therein, the said apertures being adjustable as to size. In devices of the type just mentioned, especially where a spare bag is used, the breathing device is first emptied by breathing. This is done to secure, especially at great heights, enough air from the atmosphere so as to permit a sufficient quantity of gas for filling the lungs, while the requisite amount of oxygen proper for the lungs is supplied by the breathing device itself. An imperfect fit of a mask, or a mask with apertures therein, does not furnish air in the requisite amounts at great heights.

Another serious difficulty is that in devices of this type which are provided with inhaling and exhaling valves, saliva enters the valves and freezes therein at great heights, thereby rendering the valves inoperative.

The present invention both makes possible the securing of the requisite amount of air from the atmosphere and also prevents any valve from becoming inoperative due to freezing of saliva. The inhaling and exhaling valves are positioned on opposite ends of a U-shaped tube, the valve-ends of said tube extending upwards. A breathing conduit is connected to said U-shaped tube at the inner curvature thereof. This breathing conduit may be comprised of a main pipe and a branch pipe, the main pipe connecting with the U-shaped tube at the inner curvature thereof and the branch pipe connecting with said main pipe at a point below the valves and above the point of connection of the main pipe and the U-shaped tube. The branch pipe extends outward and downward from the

main pipe and is positioned in a plane substantially at right angles to the plane of the U-shaped tube.

The device forms a complete valve unit. The free ends of the breathing conduit, or as shown, the free ends of the main pipe and branch pipe are adapted to connect with a hose so that the complete valve unit may be inserted into a breathing hose of an oxygen supplying apparatus (not shown in the drawings).

Fig. 1 of the drawings is a sectional elevation, and Fig. 2 is a side view of a construction of the device shown by way of example.

The device as shown comprises a substantially U-shaped tube 3. This tube is provided at each upwardly directed end with a shank 4, 5. The shank 4 is provided with a non-return valve comprising a cap 6 screwed on to the shank and having an opening 7 therein. Within the shank 4 is a yoke 10 which supports a spring 9 which presses against a valve plate 8. The valve 8 is opened inwardly against the action of the spring 9, the pressure of said spring preferably being adjustable.

The shank 5 at the opposite end of the U-shaped tube is provided with an exhaling valve which is comprised of a cap 11 having an opening 12, a plate or valve 13 and an annular seat 14.

A breathing conduit comprised, as shown, of pipes 1 and 16 is connected at 2 into the inner curvature of the bent portion of the substantially U-shaped tube. The pipe 16 of the breathing conduit is shown branching from pipe 1 and being positioned in a plane substantially at right angles to the aforesaid U-shaped member. The free end of the pipe 16 of the breathing conduit is adapted to connect with a hose of the oxygen supplying apparatus (not shown). The free end of pipe 1 is adapted to connect with the main hose of the oxygen supplying apparatus so that the device described as a unit is connected in the oxygen supplying hose.

The air breathed oscillates between the pipes 1 and 16 through the opening at 15.

The inner curvature or central portion of

the U-shaped tube 3 is always lower than the opening 15 and below the valves at the ends of the U-shaped tube. This lower portion of the U-shaped tube thus serves as a saliva trap, as the valves are always positioned above the point where the conduit pipe is connected to the U-shaped tube.

Air from the atmosphere is inhaled due to the following action. At the beginning of every breath only the exhaling valve 13, 14 is in use. At the end of each breath a partial vacuum or sub-pressure is created after previously emptying the air reservoir or breathing bag. Due to this partial vacuum the atmospheric pressure on the valve plate 8 from the outside is greater than the action of the spring 9 pressing against the inner surface of the plate and thus the valve plate is moved downwards, permitting air from the outside to enter the device and to be inhaled.

Having now described my invention what I claim as new and desire to secure by Letters Patent in the United States is as follows:

25 I claim:

1. In an oxygen breathing apparatus, a breathing conduit, a substantially U-shaped tube having its ends extending upwards, an inhaling valve positioned in one end of said

30 U-shaped tube, an exhaling valve being positioned in the other end of the U-shaped tube, the aforesaid breathing conduit connecting with said U-shaped tube at a point thereon below said valves.

35 2. In an oxygen breathing apparatus, a breathing conduit, a substantially U-shaped tube having its ends extending upwards, an inhaling valve positioned in one end of said U-shaped tube, an exhaling valve being positioned in the other end of said U-shaped tube, the aforesaid breathing conduit connecting with said U-shaped tube at a point thereon below said valves, the free ends of said breathing conduit adapted to connect with a

40 hose, whereby the complete unit may be connected to a hose from an oxygen supplying apparatus.

100

45 3. In an oxygen breathing apparatus, a breathing conduit, a substantially U-shaped tube having its ends extending upwards, an inhaling valve positioned in one end of said U-shaped tube, an exhaling valve being positioned in the other end of said U-shaped tube, the aforesaid breathing conduit connecting with said U-shaped tube at a point thereon below said valves, the free ends of said breathing conduit adapted to connect with a

50 hose, whereby the complete unit may be connected to a hose from an oxygen supplying apparatus, the aforesaid breathing conduit connecting with said U-shaped tube at a point thereon below said valves, the free ends of said breathing conduit adapted to connect with a

55 hose, whereby the complete unit may be connected to a hose from an oxygen supplying apparatus, said inhaling valve actuating against resistance, when due to the insufficient admission of oxygen within the device a sub-pressure or vacuum is created therein.

105

60 4. In an oxygen breathing apparatus, a

65 U-shaped tube having its ends extending up-

wards, an inhaling valve positioned in one end of the U-shaped tube, an exhaling valve positioned in the other end of said U-shaped tube, a breathing conduit comprising a pipe connecting with said U-shaped tube at a point substantially at the central portion of the inner curvature of said U-shaped tube and a branch pipe positioned in a plane substantially at right angles to the plane of the U-shaped tube and connected with said first pipe at a point below said valves and above the point at which said first pipe connects with said U-shaped tube.

5. In a valve unit for an oxygen breathing apparatus, a substantially U-shaped tube 80 with its ends extending upward, a breathing conduit connected with said U-shaped tube substantially at the center thereof, an exhaling valve positioned in one end of said U-shaped tube, an inhaling valve positioned in the other end of said U-shaped tube, said inhaling valve comprising an opening, a valve plate to cover said opening, an adjustable spring for actuating said valve plate against said opening, whereby air is admitted into 90 the device when a sub-pressure or vacuum is created in the device and the atmospheric pressure on the outer surface of the valve plate is greater than the force of the spring.

In testimony whereof I have signed my 95 name to this specification.

Dr. OTTO HEINRICH DRÄGER.
